UNITED STATES PATENT OFFICE.

ALAN FREDERIC SARGEAUNT, OF NORWICH, ENGLAND.

CHEMICAL FIRE-EXTINGUISHER.

No. 862,869.

Specification of Letters Patent.

Patented Aug. 6, 1907.

Application filed May 11, 1906. Serial No. 818,336.

To all whom it may concern:

Be it known that I, ALAN FREDERIC SARGEAUNT, a subject of the King of Great Britain, residing at Norwich, in the county of Norfolk and Kingdom of England, have invented new and useful Improvements in Chemical Fire-Extinguishers, of which the following is a specification.

This invention has for its object to render fire extinguishers more effective in operation than heretofore and likewise to simplify their construction and so reduce the cost of manufacture particularly when they are of large size.

A distinguishing feature of my invention consists in storing under pressure any suitable gas such for instance as carbon dioxide in a separate detachable gas bottle or cylinder which is mounted in any convenient manner on a frame of any preferred description and is connected by pipes controlled by a suitable valve with two separate storage vessels carried on said frame each of which vessels contains a concentrated chemical solution that is stored therein without pressure thus considerably minimizing the risk of leakage. When the extinguisher is in use such solutions together with the gas are delivered in a single combined jet immediately onto the flames whereby an important advantage is obtained as owing to the heat generated by the latter the chemical reaction set up by the mixing of the solutions is greatly intensified and results in the free evolution of an extinguishing gas and the formation of extinguishing salts which together with the gas rapidly and effectually subdue and extinguish the fire. And in order that my said invention may be readily carried into effect I will now with the aid of the accompanying drawings wherein similar letters of reference indicate corresponding parts proceed more particularly to describe and ascertain the same.

Figures 1, 2, are front and side elevations and Fig. 3 a plan partly in section and drawn to an enlarged scale of a chemical fire extinguisher made according to my invention.

a a are storage vessels each furnished with a siphon tube *b*, a discharge pipe *c* and a gas inlet tube *d*. The

discharge pipes are connected by a cock or valve *d* to a common nozzle *e* which is coupled in any convenient manner to a delivery hose *f*.

A separate detachable gas bottle or cylinder *g* serves to contain carbon dioxide or other suitable gas at a high pressure and is connected to each of the storage vessels *a a* by a union *g'*, tee piece *h*,—and gas inlet tube *i*. Such gas bottle or cylinder *g* is furnished with a valve *g*² that is operated by a key or lever *j*. The storage vessels *a a* have filling apertures through which they can be charged with suitable chemical solutions such for instance as a concentrated solution of an alum salt and a concentrated solution of sodium bicarbonate, the alum solution being placed in one vessel and the solution of sodium bicarbonate in the other. When so charged the filling apertures are closed by screw caps *k* that are fitted with washers to render such apertures gas tight. This latter requirement applies to all the other joints and connections of the extinguisher. *l* is a combination frame and trolley whereon the extinguisher may be mounted for convenience of transport when of large size. Such frame may however be of any preferred description.

When using the extinguisher the gas valve *g*² is first opened after which the discharge cock *d* is opened when the compressed gas forces the chemical solution out of each storage vessel into the common discharge nozzle *e* from which such solutions escape in the form of a single combined jet as above mentioned.

I claim,

In a portable fire-extinguisher, the combination, with two storage vessels for holding liquid fire-extinguishing chemicals under atmospheric pressure, of a discharge pipe provided with a single valve, two pipes connected with the said discharge pipe and extending within the two said vessels to the lower ends thereof, a bottle for holding gas under high pressure, detachable fastening-devices for securing the said bottle to the said vessels, and a single valve and pipe connections which connect the said bottle with the upper ends of the said vessels.

ALAN FREDERIC SARGEAUNT.
